UNITED STATES PATENT OFFICE.

JOHN LA DOW, OF TRUMANSBURG, NEW YORK, ASSIGNOR TO GREGG & CO.,
OF SAME PLACE.

HAY-PRESS.

SPECIFICATION forming part of Letters Patent No. 352,546, dated November 16, 1886.

Application filed February 5, 1886. Serial No. 190,919. (No model.)

To all whom it may concern:

Be it known that I, JOHN LA DOW, a citizen of the United States, residing at Trumansburg, in the county of Tompkins and State of New 5 York, have invented certain new and useful Improvements in Perpetual Hay-Presses, of which the following is a specification, reference being had to the accompanying drawings.

The present invention relates to improvements in perpetual hay-presses; and it consists in such combinations of elements and arrangements of parts as enable me to construct the apparatus almost entirely of wood.

The details will be fully hereinafter set forth.

15 In the drawings, Figure 1 is a side elevation of a press constructed according to my invention. Fig. 2 is a sectional elevation thereof. Fig. 3 is a top plan view, a portion of the walking-beam being broken away to more 20 clearly show the devices by which it is operated. Fig. 4 is a plan view, partly in section, taken on the line 44 of Fig. 2. Fig. 5 is an end view. Fig. 6 is a section on the line 66 of Fig. 2. Fig. 7 is a section on the line 77 of Fig. 2. Fig. 8 is a perspective view of the follower.

Similar letters denote like parts.

The friction-chamber A and the compression-chamber B, which constitute the lower portion of the apparatus, are formed of four 30 strong wooden beams, A', extending the entire length of the machine and forming the principal support for the co-operating parts. The beams A' are separated above and below at one end by the cross-pieces a, and the side pieces, 35 a', to which they are secured by screw-bolts b. The cross-pieces are recessed and arranged to allow of some adjustment through the screw-bolts referred to, and the apertures in the side pieces are elongated, as shown, by means of 40 which the friction-chamber A may be enlarged or contracted both vertically and transversely, and the resistance to the passage of the material being compressed and the consequent weight of the bale, adjusted as desired.

45 The chamber A is provided with sides A², which are suitably and permanently secured to the vertical stay-pieces a', and with top and bottom boards, A³, which are similarly secured. The top board terminates at the end of the friction-chamber, as also do the sides, but the bottom board extends rearward to the end of the

compression-chamber, forming a bottom therefor, and may be centrally slotted to allow the escape of dust and trash.

The follower C is reciprocated at the end of 55 the compression-chamber B, where it is supported upon metallic guides which, in the form of flanges C', are attached to the inner sides of the beam A'. The follower is constructed of a solid front piece or head, D, sides D', which 60 said sides are grooved at d, as shown. Metallic strips D² extend rearwardly and lengthen the supports of the follower, resting upon the guides C'. Hollow bosses d', formed with suitable side extensions, are securely bolted to the 65 inner sides of the side pieces D', and are adapted to receive the projections on pivot-plates d², which are secured on both sides of the end of the wooden pitman D³ connecting the follower to the crank D⁴, by which it is 70 driven. A connecting-pin, d³, passes transversely through the end of the pitman and through the pivot-plates and hollow bosses and into the wooden side pieces D', making a firm and secure connection between the pitman and 75 follower. The crank-shaft D⁵ is mounted in suitable bearings near the rear end of the frame, which frame is re-enforced and strengthened by vertical blocks or stays d⁴ d⁵, inserted between the upper and lower timbers, A', and 80 carries the geared wheel D⁶, which meshes with pinion D⁷, and is connected through geared wheel D⁸ with pinion D⁹ and the belt-wheel E, from which it will be readily understood how the necessary reciprocating motion is 85 communicated to the pitman and follower during the operation of the machine.

The sides of the compression-chamber are tightly closed by boards e, which extend from the blocks d⁴ to the extremity of the friction-chamber, being there securely held by the side pieces, a'.

Extending upward from above the rearward position of the follower is a fixed bulk-head, F, and supported upon suitable horizontal supports is a condenser-box formed of the sides f, tail-board g, and end G. The box is reciprocated at each movement of the follower, and the material therein contained is concentrated between its end G and the head F.

Above the condenser-box and upon suitable supports is placed a hopper, H, provided with

a bottom, preferably of thin sheet metal, under which the tail-board passes when the box moves back to receive its charge, which is then pushed into it from the hopper. As the condenser moves forward to concentrate the charge, the tail-board closes the space in front of the hopper and prevents the material from descending until the box is again in position to receive it. Standards I I are secured to the upper hopper-frame, and provided at their inner sides with guide-strips *i*, between which is mounted the feeder-board *J*, that is actuated by the walking-beam *J'*, supported and operated as follows: A rock-frame, *K*, is pivoted upon on axis, *K'*, mounted in brackets *K*², near the rear end of the main frame, and further secured by iron braces *L*, attached to the frame-timbers, and through the upper end of which the said axis passes. Upon this axis is mounted a pair of upwardly-extending links or arms, *k*, which carry the walking beam *J'*, and, being pivotally mounted, permit the outer end thereof, together with the feeder to which said outer end is pivotally connected, to move vertically without the interposition of links or other mechanical expedients. The remainder of the axis is covered by pipe-sleeves, which allow of its being firmly secured in position without cramping the supporting-frame. The forward extremity, *k'*, of the rock-frame carries connecting-links *k*², which are attached to the walking-beam, and impart rapid and positive upward and then downward movement thereto and to the feeder *J*.

When the feeder is in its elevated position, the lowest portion, *K*³, of the rock-frame is in the path of the crank end of the pitman, which, striking it, throws it upward and the walking-beam and feeder downward. Projections or cams *L'* are secured on either side of the frame *K* in the path of the cranks *D*⁴, which will strike them after the depression of the feeder, and forcing the rock-frame upward will quickly return it to its first position, bringing the lower end, *k'*, again into the path of the pitman *D*³. The condenser is moved by means of pitmen *l l*, which are pivoted upon metallic plates *f*', secured thereto, the pitmen being actuated by vibrating arms *M*, suitably pivoted to the main frame and connected to the pitman *D*³ by links *m*, thus giving the condenser a movement coinciding with that of the follower, and which can be lengthened or shortened by altering the point of connecting the links *m* to the vibrating arm *M*. The charge having been transferred from the hopper to the condenser, and thence by the feeder to the compression-chamber, and there compressed against the resistance of the accumulated charges in the friction-chamber, is automatically secured in position by spring-dogs, which, being forced outward by the passing charge, immediately return and take position behind it, while the follower is at the forward end of its stroke.

The side dogs, *N*, are pivoted in the spaces between the side and top and bottom pieces and hinge upon suitable vertical bolts passing

through the timbers. They are provided with retracting-springs *n*, that are placed upon short bolts *n'*, extending laterally through the support, and acting to limit the inward movement of the dogs.

Across the top of the compression-chamber is placed a spring-actuated retaining-bar, *O*, which is faced with sheet metal at its under side, and secured at its ends to arms *O'*, pivoted to the frame-timbers. The bar *O* is depressed by suitable springs, *P*. The follower being notched at its sides to receive the spring-dogs *N*, and the upper side of the compression-chamber being open, when the charge has been compressed the dogs and retaining-bar spring into position and retain it until the operation is repeated and a fresh charge takes its place. Follower-boards are placed in the compression-chamber in the usual manner, and as the charges accumulate and are gradually forced along the friction-chamber toward the exit at its open end, the wires are inserted through the open sides and the grooves in the follower-boards, and the bales tied and then discharged in the well-known manner.

Having described my invention, what I claim is—

1. In a hay-press, the combination, with suitable compressing and condensing chambers, of a follower, a crank and pitman for reciprocating the follower, the pivoted rock-frame *K*, the lower portion of which, *K*³, is located in the path of the pitman and the upper portion of which is provided with cams *L'*, the walking-beam *J'*, the feeder *J* and suitable supports therefor, and connections between the rock-frame and walking-beam, whereby the latter is positively actuated at each movement of the rock-frame, as set forth.

2. In a hay-press, the combination, with compressing and friction chambers framed as described, a follower, a pitman, a crank, and suitable wheel-work for reciprocating the follower, of the rock-frame *K*, supported upon axis *K'*, with its lower portion, *K*³, located in the path of the pitman, a walking-beam, *J'*, having arms *k* secured thereto and supported upon axis *K'*, and links *k*², extending from the outer end of frame *K* and pivotally secured thereto, whereby the walking-beam is oscillated whenever the pitman strikes the lower end of the rock-frame, and a feeder, *J*, pivotally connected to the outer end of the walking-beam and actuated positively by the movements thereof, as set forth.

3. In a hay-press, the follower *C*, consisting of the wooden head *D*, side pieces, *D'*, extension-guides *D*², and hollow bosses *d*', in combination with suitable pitman provided with pivot-plates *d*², and a connecting-pin, *d*³, as set forth.

In testimony whereof I hereto affix my signature in presence of two witnesses.

JOHN LA DOW.
